HITCHING DEVICE

Starling Winters, Englewood, N. J.

Application June 2, 1943, Serial No. 489,359

10 Claims. (Cl. 280—33.15)

(Granted under the act of March 3, 1883, as amended April 30, 1928; 370 O. G. 757)

The invention described herein may be manufactured and used by or for the Government for governmental purposes, without the payment to me of any royalty thereon.

The present invention pertains to a novel device for hitching a towed vehicle to a tractor.

The principal object of the invention is to eliminate end play and side play due to looseness in the connection to the pintle of the tractor. The damaging results of end play and side sway are well known, among which are breakage of vital parts and curtailment of the maximum safe speed.

This object is accomplished by the action of a vise jaw movable in a lunette and mechanism whereby the initial pull on the lunette tightens the jaw against the pintle. This mechanism is preferably hydraulic and includes the pistons attached respectively to the lunette and the jaw. The cylinders for the pistons are in communication with each other only when pressure is exerted by the lunette-operated piston. The latter is so proportioned as to exert the proper pressure on the other piston and the jaw carried thereby. This pressure thus becomes trapped behind the jaw piston and secures the jaw substantially rigidly in its clamping position. The trapped pressure may be relieved by manually opening a check valve, whereupon the jaw piston and the jaw are retracted by the action of a spring which was previously compressed on the pressure stroke of the piston.

The invention is fully disclosed by way of example in the following description and in the accompanying drawing in which:

Figure 1 is a top plan view of the device, partly in section;

Figure 2 is a longitudinal vertical section, partly in elevation, and

Figure 3 is an enlarged detail vertical section.

Reference to these views will now be made by use of like characters which are employed to designate corresponding parts throughout.

Each of the figures shows a main cylinder 1 lying on a horizontal axis and formed with a reservoir 2 at a higher level so that the hydraulic fluid used in the system may flow by gravity from the reservoir to the cylinder as will presently be described. The cylinder is formed with a pair of lateral apertured flanges 3 or other suitable means for attaching the device to the A-frame of the towed vehicle. The top of the reservoir is fitted with a cover plate 4 which may be welded in place, and in the plate is inserted a fill plug 5.

A vise cylinder 7 is extended forwardly and co-

axially from the main cylinder 1 and may be integral therewith. Suitable reinforcing ribs 8 are provided along the cylinder 7. The cylinder 7 is extended somewhat into the cylinder 1 by means of a thickened wall portion 9 within the latter, as shown in Figure 2.

In the vise cylinder 7 is mounted a vise piston 10 from which extends a tubular piston rod 11 through the forward end of the cylinder. The piston 10 has a suitable packing 12 fitted in the cylinder 7. On the forward or external end of the rod 11 is secured a vise member 13 by screws 14. The forward end of the vise member carries a pin 15 on which is pivotally mounted a lunette 16 vise jaw 16.

A lunette piston rod 17 is slidably mounted in the tubular piston rod 11, projecting forwardly therefrom into the vise member 13 and rearwardly for some distance into the main or lunette cylinder 1. At the latter end, the piston rod 17 carries a piston 18 fitted in the cylinder 1 and having suitable packing 19. The rear end of the cylinder 1 is closed by a loosely fitted cap 20. The forward end of the piston rod 17 is formed with a lunette 21 enclosing the jaw 16. The vise member 13 consists of a pair of arms, as shown in Figures 1 and 2, between which the rearward portion of the lunette is received.

The rear end of the vise cylinder 7 within the lunette cylinder 1 has secured thereto a diaphragm plate 22 by bolts 23. This plate has a packing assembly 24 fitted around the piston rod 17 and secured by a retaining plate 25 and screws 26. The rear end of the vise cylinder 7 communicates with the reservoir 2 through a passage 27 in the enlarged cylinder wall 9. In this passage is fitted a check valve 28 extending into the reservoir and normally held closed by a spring 29.

Another passage 30 extends from the passage 27 through the plate 22 to the cylinder 1, and in this passage is mounted a check valve 31 opening towards the passage 27 and normally held closed by a spring 32. A relief valve 33 for the cylinder 1 is mounted in the bottom of the reservoir 2. This valve opens toward the cylinder 1 and is normally closed by a spring 34.

In the operation of the device, it may be assumed that the vise jaw 16 is initially retracted within the lunette 21 as shown. The lunette is then placed in the pintle 35 in the usual manner. The tractor is then started, producing a pull on the lunette and its piston rod 17. Before the trailer vehicle moves forward, the lunette piston 18 advances, transferring fluid through the check valve 31 and passages 30, 27 to the vise cylinder

1. The vise piston 10 is thus moved forward until the vise jaw 16 comes into contact with the rear of the pintle. The size of the lunette piston is properly determined to this operation. In this manner, all play in the hitch is taken up. The vise remains tight even when the tractor exerts no pull, because the oil in the vise cylinder has no means of escape.

To unhitch the vehicles, the check valve 28 is opened by pressure on a spring raised plunger 36 slidably mounted in the cover plate 4 and positioned in line with the valve. A spring 37 disposed in the cylinder 7 between its forward end and the piston 10 and which has previously been compressed is now permitted to expand due to the relief of the cylinder 7 through the check valve 28. The piston rod 17 is thus retracted, carrying with it the vise member 13 and vise jaw 16.

When the vise jaw has reached its limit within the lunette, the manual pressure on the plunger 36 is discontinued. The lunette is now lifted out of the pintle. Further pressure on the plunger 36 permits another rearward movement of the vise jaw in the manner described, and the jaw engages the rear end of the lunette to move the latter rearwardly. The rearward motion of the lunette piston 18 draws oil into the lunette cylinder 1 from the reservoir through the relief valve 33, in preparation for the next hitching operation. The rear end of the cylinder 1 is vented beneath the loosely fitted cap 20.

It may now be seen that the initial pull of the tractor on the lunette tightly clamps the pintle between the jaw 16 and the forward end of the lunette 21. Side sway is a function of looseness at the pintle and is therefore substantially eliminated because of the tight grip on the pintle.

Although a specific embodiment of the invention has been illustrated and described, it will be understood that various alterations in the details of construction may be made without departing from the scope of the invention as indicated by the appended claims.

What I claim is:

1. A hitching device comprising a lunette, a vise jaw movable in said lunette, means for advancing said jaw in the lunette, and an operative connection between said means and said lunette and operable by a pull on said lunette to move said means and to thereby advance the jaw.

2. A hitching device comprising a lunette, a vise jaw movable in said lunette, hydraulic means for advancing said jaw in the lunette, and an operative connection between said means and said lunette and operable by a pull on said lunette to move said means and to thereby advance the jaw.

3. A hitching device comprising a lunette, a vise jaw movable in said lunette, pistons attached respectively to said lunette and jaw, a lunette cylinder and a vise jaw cylinder for said pistons, a one-way means of communication between said cylinders adapted to open under pressure from the lunette-operated piston, whereby to advance the other piston and said jaw relatively to said lunette.

4. A hitching device comprising a lunette, a vise jaw movable in said lunette, pistons attached respectively to said lunette and jaw, a lunette cylinder and a vise jaw cylinder for said pistons, a one-way means of communication between said cylinders adapted to open under pressure from the lunette-operated piston, whereby to advance the other piston and said jaw relatively to said lunette.

tively to said lunette, manually releasable means for trapping pressure in said vise jaw cylinder, and a spring adapted to retract said jaw in said lunette on release of said means.

5. A hitching device comprising a lunette, a vise jaw movable in said lunette, pistons attached respectively to said lunette and jaw, a lunette cylinder and a vise jaw cylinder for said pistons, a one-way means of communication between said cylinders adapted to open under pressure from the lunette-operated piston, whereby to advance the other piston and said jaw relatively to said lunette, a spring in said vise jaw cylinder adapted to be energized on advance of the piston attached to said jaw, and manually releasable means for trapping pressure in said vise jaw cylinder in opposition to said spring.

6. A hitching device comprising a lunette, a vise jaw movable in said lunette, pistons attached respectively to said lunette and jaw, a lunette cylinder and a vise jaw cylinder for said pistons, a one-way means of communication between said cylinders adapted to open under pressure from the lunette-operated piston, whereby to advance the other piston and said jaw relatively to said lunette, a reservoir having a connection to said vise jaw cylinder, manually releasable means for trapping pressure in said vise jaw cylinder, and a spring adapted to retract said jaw in said lunette on release of said means.

7. A hitching device comprising a lunette, a vise jaw movable in said lunette, pistons attached respectively to said lunette and jaw, a lunette cylinder and a vise jaw cylinder for said pistons, a one-way means of communication between said cylinders adapted to open under pressure from the lunette-operated piston, whereby to advance the other piston and said jaw relatively to said lunette, a reservoir having a connection to said vise jaw cylinder, manually releasable means for trapping pressure in said vise jaw cylinder, and a spring adapted to retract said jaw in said lunette on release of said means.

8. A hitching device comprising a lunette, a vise jaw movable in said lunette, pistons attached respectively to said lunette and jaw, a lunette cylinder and a vise jaw cylinder for said pistons, a one-way means of communication between said cylinders adapted to open under pressure from the lunette-operated piston, whereby to advance the other piston and said jaw relatively to said lunette, a spring in said vise jaw cylinder adapted to be energized on advance of the piston attached to said jaw, a reservoir having a connection to said vise jaw cylinder, manually releasable means for trapping pressure in said vise jaw cylinder, and a spring adapted to retract the jaw in said lunette on release of said means.

9. A hitching device comprising a lunette, a vise jaw movable in said lunette, pistons attached respectively to said lunette and jaw, a lunette cylinder and a vise jaw cylinder for said pistons, a one-way means of communication between said cylinders adapted to open under pressure from the lunette-operated piston, whereby to advance the other piston and said jaw relatively to said lunette, a reservoir having a connection to said vise jaw cylinder, manually releasable means for trapping pressure in said vise jaw cylinder, and a spring adapted to retract said jaw in said lunette on release of said means, and a relief valve between said reservoir and said lunette cylinder and adapted to open on reduced pressure in said cylinder.

10. A hitching device comprising a lunette, a vise jaw movable in said lunette, pistons attached respectively to said lunette and jaw, a lunette cylinder and a vise jaw cylinder for said pistons, a one-way means of communication between said cylinders adapted to open under pressure from the lunette-operated piston, whereby to advance the other piston and said jaw relatively to said lunette, a reservoir having a connection to said

vise jaw cylinder, means for trapping pressure in said vise jaw cylinder, a spring adapted to retract said jaw in said lunette on release of said means, and a plunger mounted in said reservoir for releasing said means, and a relief valve between said reservoir and said lunette cylinder and adapted to open on reduced pressure in said cylinder.

STARLING WINTERS.
